UNITED STATES PATENT OFFICE

140,439

DESIGN FOR A CHIME ACTUATOR

Joseph R. Corbett, Cincinnati, Ohio, assignor to
Nu Tone, Incorporated, New York, N. Y., a
corporation of New York

Application November 14, 1944, Serial No. 116,329

Term of patent 7 years

(Cl. D72—1)

To all whom it may concern:

Be it known that I, Joseph R. Corbett, a citizen of the United States, residing at Cincinnati, in the county of Hamilton and State of Ohio, have invented a new, original, and ornamental Design for a Chime Actuator, of which the following is a specification, reference being had to the accompanying drawing, forming a part thereof.

Figure 1 is a perspective view of a chime actuator showing my new design.

Figure 2 is a side elevational view thereof.

Figure 3 is a bottom plan view.

I claim:

The ornamental design for a chime actuator, substantially as shown.

JOSEPH R. CORBETT.
